United States Patent Office

Des. 196,885
Patented Nov. 12, 1963

196,885

TELEVISION PROJECTOR

Richard J. Zeitler, Danbury, Conn., assignor to Waltham
Precision Instrument Company, Inc., Waltham, Mass.,
a corporation of Massachusetts

Filed June 4, 1962, Ser. No. 70,400

Term of patent 14 years

(Cl. D61—1)

FIG. 1 is a side elevational view of a television projector showing my new design, the side opposite thereto being the same in appearance.

FIG. 2 is a front elevational view thereof.

FIG. 3 is a rear elevational view thereof.

FIG. 4 is a front perspective view.

I claim:

The ornamental design for a television projector, as shown and described.
